UNITED STATES PATENT OFFICE.

MURDOCH J. MCNEIL, OF LINCOLN, NEW HAMPSHIRE.

REFRIGERATOR.

SPECIFICATION forming part of Letters Patent No. 553,175, dated January 14, 1896.

Application filed October 17, 1895. Serial No. 565,992. (No model.)

To all whom it may concern:

Be it known that I, MURDOCH J. MCNEIL, formerly of Nova Scotia, but having declared my intention of becoming a citizen of the 5 United States, residing at Lincoln, in the county of Grafton and State of New Hampshire, have invented certain new and useful Improvements in Refrigerators; and I do hereby declare the following to be a full, clear, and 10 exact description of the invention, such as will enable others skilled in the art to which it appertains to make and use the same.

My invention relates to improvements in refrigerators, and especially in that class of 15 refrigerators intended for use with butter, cream, or other like articles, which readily absorb the odor and flavor of other articles that may have been placed in the refrigerator at some prior time.

20 The said invention consists in certain novel features of construction and combination and arrangement of parts, as will be hereinafter more fully described and claimed.

Figure 1 represents a front view of the improved refrigerator. Fig. 2 represents a section along the line 2 2 of Fig. 3. Fig. 3 represents a section along the line 3 3 of Fig. 2, and looking down, and Fig. 4 represents a section along the line 4 4 of Fig. 2, and looking down.

25 A represents a box or casing made of wood or other non-conducting material and provided with four corner-posts A² and four bottom boards A' curved upward, as at a, and 30 united at their lower outer ends to form steps for the casters a'.

B represents the bottom of the refrigerator, which is made of wood or other suitable non-conducting material, and is faced with plates 40 of glass b. The center of this bottom is cut away, as at b⁰, which open space is inclosed by the frame b², over which frame is provided a sloping cap-piece b³. Beneath the said frame the opening b⁰ is closed by the bottom 45 plate B', which is provided with a drain-pipe b' for the water formed by the melting of the ice. Two of the sides of the refrigerator are closed by glass panels C, while the opposite sides are closed by the swinging doors D, 50 which are also provided with glass panels d, by means of which four panels the interior of the refrigerator is at all times kept well

lighted, while at the same time the glass is a sufficiently good non-conductor of heat, and also retains the cold air within the refrigerator.

The top of the refrigerator is closed by the doors E which open upward, as shown in Fig. 2.

F represents a frame set across the refrigerator toward the upper end thereof, and covered with a floor of zinc f or other metal. This floor is also cut away in its center, the hole formed therein being surrounded by the square frame f', while two of the outer ends 60 of the floor do not extend entirely out to the casing A, leaving air-passages f⁰ to allow for the circulation of air in the refrigerator. Around the outer ends of the rectangular floor is a chock f² to support the outer edges of the 65 metal ice-bottom H, on which the ice is supported. By means of these chocks the said bottom H is made somewhat funnel-shaped, and the water from the melting ice flows down into the central chamber and out through the 70 drain-pipe b'. Two of the outer edges of the 75 ice-bottom H are turned up, as shown at h, to allow the circulation of air between the said ends and the casing A.

A number of stout metal bars K are secured 80 between the frame f' and the frame b², which bars should be close enough to prevent any considerable portions or corners of the ice from projecting far enough between the said bars to strike and break the inner glass panels 85 L, which are also secured between the said frames f' and the bottom of the refrigerator parallel to said bar.

It will thus be seen that a refrigerator is provided in which there is a central ice-chamber 90 for the smaller blocks of ice m, which chamber is formed with glass walls and metal bars protecting the said walls, while the major portion of the ice, in the form of the blocks M, is placed in the upper chamber. In this 95 manner an extremely neat-looking, showy, and efficient refrigerator is provided, eminently adapted for the preservation and exhibition of butter, cream, fruits, game, or other food products.

The boards forming the bottom B and also the side panels C are detachably connected, as by means of screws, to the refrigerator, so that they may be readily removed and new

panes of glass substituted in case the old ones are broken. Moreover, the bottom H is detachably mounted in the upper ice-chamber, whereby it may be taken out and cleaned and 5 the bottom plates f may be cleaned when desired.

It will be seen that nearly all of the inner surface of the refrigerating-chamber is lined with glass, which is absolutely non-absorbent 10 of the flavors or odors given out by the various articles which may be placed in the refrigerator.

The various other advantages of the herein-described construction and arrangement of 15 parts will readily suggest themselves to any practical mind.

Having thus described my invention, what I claim, and desire to secure by Letters Patent of the United States, is—

20 1. A refrigerator provided with an upper ice chamber with a sloping bottom, with a perforation in the center thereof, a central ice chamber located below said perforation and provided with a drain pipe, with metal 25 bars surrounding said chamber, and glass panels exterior to said bars, a glass covered bottom surrounding the lower end of said central ice chamber, and glass panels in the sides of the refrigerator, exterior to said central ice 30 chamber, substantially as described.

2. A refrigerator provided with an upper ice chamber having a funnel-shaped bottom

with an opening in the center thereof, a central ice chamber located below said opening and provided with a drain pipe, metal bars 35 surrounding said chamber, and glass panels exterior to said bars, a glass covered bottom in the lower portion of said refrigerator, glass panels extending from said bottom to the base of the upper ice chamber, and swinging 40 glass doors provided on the opposite sides between said panels, substantially as described.

3. A refrigerator provided with an upper ice chamber having a funnel-shaped bottom with an opening in the center thereof, and air 45 passages between the outer edges of the said bottom, and the inner walls of the refrigerator, a central ice chamber located below said opening and provided with a drain pipe, metal 50 bars surrounding said central chamber, glass panels exterior to said bars, and shutting in the said central chamber, a glass covered bottom in the lower portion of said refrigerator, glass panels extending from said bottom to the base of the upper ice chamber, and 55 swinging glass doors provided on the opposite sides between said panels, substantially as described.

In testimony whereof I affix my signature in presence of two witnesses.

MURDOCH J. MCNEIL.
